UNITED STATES PATENT OFFICE.

JAMES DONOVAN, OF THREE RIVERS, MICHIGAN, ASSIGNOR, BY MESNE ASSIGNMENTS, TO SHAFFIELD CAR COMPANY, OF THREE RIVERS, MICHIGAN, A CORPORATION OF MICHIGAN.

HAND-CAR FRAME.

No. 811,042.

Specification of Letters Patent.

Patented Jan. 30, 1906.

Application filed April 10, 1905. Serial No. 254,901.

To all whom it may concern:

Be it known that I, JAMES DONOVAN, a citizen of the United States, residing at Three Rivers, in the county of Wayne and State of Michigan, have invented certain new and useful Improvements in Hand-Car Frames, of which the following is a specification, reference being had therein to the accompanying drawings.

10. The invention relates to frames for light cars—such as hand-cars, push-cars, &c.; and it consists in a metallic frame which is light, strong, and cheaply constructed, also in a frame made of sheet metal and preferably struck from a single piece comprising sills and ties, and in the construction and arrangement of the various parts, as more fully hereinafter described, and particularly pointed out in the claims.
20. In the drawings, Figure 1 is a perspective view of a hand-car frame embodying my invention. Fig. 2 is a cross-section thereof on line *x x*. Fig. 3 is a section on line *y y*. Fig. 4 is a section through one of the axle-boxes to show the manner of connecting the axle to the frame; and Fig. 5 is a side elevation of a portion of the frame, showing the front axle-box bracket.

In making my frame, as particularly herein illustrated, I take a single sheet of metal of size sufficient to make the entire frame and with suitable dies shape it as shown in Fig. 1, consisting of the side sills *A*, the two intermediate sills *B*, and ties connecting the sills. These ties for the hand-car are preferably the two end ties *C* and intermediate ties. I have shown three intermediate ties, those near the ends *E* extending in line clear across and the middle tie comprising the two side sections *a* and the middle section *b* offset from the line of the sections *a* to form the wall or opening *F*, over which the gallows-frame stands, the base of this frame being indicated at *G*. The sills and ties I preferably flange, or form in the shape of channels, and this may be done in a single pressing operation between dies, at the same time the metal between the sills and cross-sills and ties being struck out. The side sills I preferably make deeper than the intermediate portion of the frame, as by forming the channel portion *c*

above the plane of the intermediate frame portion, the side *d* extending down below the intermediate channels. This allows one to secure the flooring *H* on the frame between the channels *c* of the side sills and substantially flush therewith. The outer faces of the end ties *C*, *I* practically extend down flush with the sides *d* of the side sills. 55

I represents stiffening members for the frame. I prefer to extend these through the channels in the sills, as shown, using pipe or tubes, and extend them through apertures in the end ties, letting them project to form handles *J*, by which the car may be lifted 60 about. The bolts *K*, which secure the gallows-frame in position, passing through the two intermediate pipes *I* keep them from end-wise displacement.

L represents blocks or brackets secured by 70 lateral bolts *M*, which pass through the sides *d* and through the side pipes *I* and which have the journal-bearings *O* thereon for the axles *P*, having wheels *Q*, as usual. I also employ the vertical bolts *R* for these blocks 75 and journal-bearings.

While I have shown and prefer to make the frame from a single sheet of metal, I believe in certain features my invention includes other ways of making the frame. 80

Instead of cutting out all of the metal between the sills I may simply depress one or more sections—such, for instance, as shown at *S*—and form these sections with the bottom plate *T* to make receptacles for tools, the 85 floor being omitted from over such sections.

What I claim as my invention is—

1. In a light car, a frame comprising longitudinal sills and ties, struck from a single sheet of metal.
2. In a light car, a frame comprising side sills, two separated intermediate sills, and connecting-ties, struck from a single sheet of metal.
3. In a light car, a frame comprising inverted channel-sills and ties, struck from a single piece of metal.
4. In a light car, a frame comprising sheet-metal intermediate sills, laterally-extending integral ties and side sills, the ties connecting 95 to the side sills below the top thereof.
5. In a light car, a frame formed of a single

- sheet of metal and comprising longitudinal intermediate sills, ties and side sills, the ties connecting to the side sills below the top.
6. In a light car, a frame; longitudinal inverted channel-sills, longitudinal stiffening members secured in the channel, and ties connecting the sills.
7. In a light car, a sheet-metal frame comprising inverted channel sills and ties, and tubular stiffening members extending through the channels of the sills.
8. In a light car, a frame comprising sills and ties in inverted channel form, struck from a single piece of sheet metal, and stiffening-bars extending through the channels of the sills, and through the sides of the end ties.

10. In a light car, such as a hand-car, an integral sheet-metal floor-frame having vertical flanges.

11. In a light car, such as a hand-car, a metallic frame comprising integral channel sills and ties.

12. In a light car, such as a hand-car, a metallic frame comprising sills and ties of inverted channels, the side sills projecting above the plane of the top of the frame.

13. In a light car, a frame comprising sills and ties, struck from a single sheet of metal, and sections such as S between the sills and ties having the bottom plate T.

In testimony whereof I affix my signature in presence of two witnesses.

JAMES DONOVAN.
